UNITED STATES PATENT OFFICE.

NELSON J. QUINN, OF TOLEDO, OHIO.

THERMOSTATIC VALVE.

Application filed January 18, 1928. Serial No. 247,538.

The present invention relates, as indicated, to a thermostatic valve, and the primary object thereof is to provide a valve of the type indicated which will be quite sensitive 5 to temperature changes, which will be small, simple, and compact, and which may be used to advantage in the cooling systems of internal combustion engines.

In cold weather, the circulation of the cooling medium through the water jacket of an internal combustion engine is deleterious rather than beneficial during approximately the first few minutes of operation. The engine is not brought to a proper operating 15 temperature because of the flow of cold liquid about the cylinders, and the consequence is that a large volume of raw liquid gasoline is deposited in the cylinders there to thin the lubricating oil, deter combustion, 20 and cause undue friction between the moving parts in the cylinders. Various devices for preventing such circulation of cooling medium have been suggested before, and I am aware of the fact that the provision of a 25 thermostatically operated valve in a cooling system is not broadly new. All of the devices of this general type which are known to me are, however, quite complicated. It is my purpose to provide a device of this 30 type of great simplicity. Furthermore, a great number of these devices are responsive not only to temperature changes, but also to pressure changes, and are consequently somewhat dangerous. To the accomplishment of 35 the foregoing and related ends, said invention, then, consists of the means hereinafter fully described and particularly pointed out in the claims.

The annexed drawing and the following 40 description set forth in detail certain mechanism embodying the invention, such disclosed means constituting, however, but one of various mechanical forms in which the principle of the invention may be used. 45 Fig. 1 is a diagrammatic representation of a portion of the cooling system of an internal combustion engine showing my valve installed therein; Fig. 2 is a transverse vertical section of one form of my 50 valve upon an enlarged scale, the valve being shown closed; Fig. 3 is a similar view, the valve being shown in open position; Fig. 4 is a sectional view of a modified form of valve; Fig. 5 is a plan view of the modification shown in Fig. 4; and Fig. 6 is a still further modification.

Referring more particularly to the drawings, the reference numeral 1 indicates an automobile radiator having an inlet connection 2; while 3 represents a cylinder block having an outlet connection 4. The connections 2 and 4 are joined normally by a short length of rubber hose 5. According to my invention, I insert within this hose 5 a metallic tube 6 within which is mounted a 60 thermostatically operated valve 7. Of course, it is to be understood that this tube 6 may as well be mounted in one of the metallic connections as 2 or 4, or in a chamber especially built for it by the manufacturer. 70 However, the fact that the tubing 6 may be inserted within the usual hose connection of an automobile without the use of tools of any sort, is a decided advantage, in that the device may be easily installed in cars already 75 on the market, and may be easily removed for inspection or repair.

The valve 7 is preferably formed of thermostatic material; i. e., said valve is bimetallic in construction. Such valve is pivoted 80 mounted as at 8, and an arm 9 is secured to one end of the valve while an arm 10 is secured to the opposite end thereof. While I have illustrated a butterfly type of valve, it is to be understood that I do not 85 intend to limit myself to this particular type of valve. A third arm 11 is secured to the valve 7 at a point between its ends.

The arm 9 carries a pivot 12 which extends through a slot 13 in one arm 14 of a 90 bell crank lever. The arm 10 carries a pivot 15 which passes through said arm 14 adjacent the angle of the lever. The other arm 16 of said lever is pivoted as at 17 to one end 18 of a lever pivoted at 19 to the free 95 end of the arm 11. The opposite end 20 of said lever is pivoted as at 21 to one end of a link 22, the opposite end of which is pivoted as at 23 to a staple 24 secured in the wall of the tubular member 6.

It will be seen that, as the ends of the valve 7 curl upwardly in response to a rise in temperature, the arms 9 and 10 will cause a clockwise rotation of the bell crank lever which will cause a straightening of the 105 toggle formed by the link 22 and the lever 18-20, thus forcing the valve to rotate in a clockwise direction about its axis 8.

The modification disclosed in Figs. 4 and 5 is similar to that disclosed in Figs. 2 and 110 3, but the valve proper 7' is not bi-metallic in character, but carries a longitudinally

extending bi-metallic strip 25 secured to said valve 7' by means of a bolt 26, and separated therefrom by a washer 27. Arms 9' and 10' are carried by the strip 25 and are 5 adapted to be secured to members of any form of linkage which will cause the desired actuation of the valve.

Fig. 6 discloses a bi-metallic valve 7" formed with a transversely extending concavo-convex depression adjacent its transverse center line. This depression tends to prevent curling of the valve about a longitudinal axis, while simultaneously aiding in curling of the valve about a transverse 15 axis.

It is to be understood that the particular form of linkage which I have illustrated is not important but that the valve may be operated by any type of linkage which will 20 effect the desired actuation upon thermo-responsive curling of the valve member 7 or strip 25.

Other modes of applying the principle of my invention may be employed instead of 25 the one explained, change being made as regards the mechanism herein disclosed, provided the means stated by any of the following claims or the equivalent of such stated means be employed.

30 I therefore particularly point out and distinctly claim as my invention:

1. A valve comprising a housing, a bi-metal valve member in said housing and means connected to said valve member to

cause thermostatic flexure of said valve member to impart opening and closing movement to said valve member. 35

2. In a valve, a housing, a bi-metal valve member, and means connected to said valve member and to said housing for causing 40 thermostatic flexure of said valve member to impart opening and closing movement to said valve member.

3. A valve comprising a housing, a bi-metal butterfly valve member pivoted in 45 said housing, and means connected to said valve member to convert thermostatic flexure of said valve member into rotary movement of said valve member about its pivot. 50

4. A valve comprising a housing, a bi-metal butterfly valve member pivoted in 55 said housing, and means connected to said valve member to convert thermostatic flexure of said valve member into rotary movement of said valve member about its pivot, said valve member being formed with a concavo-convex bead transversely thereof. 55

5. A valve comprising a housing, a butterfly valve pivoted in said housing, and a 60 linkage connected to said valve member and to said housing and adapted to convert curling of said valve member on a transverse axis to rotation of said valve member about its pivot. 60

Signed by me this 11th day of January, 65
1928.

NELSON J. QUINN.
